UNITED STATES PATENT OFFICE.

JEREMIAH KELLER, OF CANTON, OHIO, ASSIGNOR TO THE TIMKEN ROLLER BEARING COMPANY, OF CANTON, OHIO, A CORPORATION OF OHIO.

ROLL-GAUGING MACHINE.

Application filed January 24, 1925. Serial No. 4,539.

My invention relates to roll gauging machines and has for its principal object a machine that will gauge taper rolls, such as those used in roller bearings for taper, roundness and size; that is, a machine that will automatically separate from the rolls that pass through the machine all rolls that are out of round and all rolls that are off taper and that will assort according to their sizes the rolls that are satisfactory as to taper and roundness. In my copending application Serial Number 657,644, filed August 15, 1923, that part of the machine that gauges the rolls for taper and roundness is shown and fully described, and reference is hereby made to such description. The present application shows the connections between the two parts of the machine and sets forth in detail the size gauging part of the machine. The invention consists principally in a size gauging machine in which the rolls are carried by a carrier that has an intermittent rotary movement. The invention further consists in the gauging mechanism and machine and in the parts and combinations and arrangements of parts hereinafter described and claimed.

In the accompanying drawings, which form part of this specification and wherein like reference numerals refer to like parts wherever they occur, and wherein parts that are shown in said application Serial Number 657,644 have the same reference numerals as in said application.

Fig. 1 is a vertical sectional view of a roll size gauging machine embodying my invention, the feed from the roundness and taper gauging part of the machine being shown;

Fig. 2 is an elevation of the mechanism for operating the plunger that trips and reseats the ejecting devices;

Fig. 3 is an elevation of the mechanism for feeding rolls from the taper and roundness gauging part of the machine to the size gauging part;

Fig. 4 is a partial top plan view of the gauging machine, showing a portion of the size gauging part of the machine and also showing the taper and roundness gauging part of the machine;

Fig. 5 is a sectional view of the roll holding mechanism on the line 5—5 of Fig. 4;

Fig. 6 is an elevation, on an enlarged scale, of a roll holding member;

Fig. 7 is a fragmentary vertical section showing the means for ejecting a roll from a roll holder;

Fig. 8 is a wiring diagram of the size gauging machine; and

Fig. 9 is a chart showing the sequence of operations of the important parts of the machine;

Fig. 10 is a horizontal sectional view of the taper and roundness gauging part of the machine; and

Fig. 11 is a fragmentary vertical sectional view thereof showing the taper and roundness gauging devices.

Secured to a base 201 as by screws 202 is a column 203 to which is secured a bushing 204 as by keys 205. Rotatably mounted on said bushing 204 is a table 206 having a depending bearing portion 207 whose lower end rests on an anti-friction ring 208. A portion of the table overhangs the distributing disk 85 of the roundness and taper gauging machine. Mounted in pockets in the upper surface of said anti-friction ring 208 are pads of felt 209 or the like that may be kept saturated with oil. The bushing 204 preferably has a conical outer surface, so that by moving it endwise, looseness and wear of the table may be taken up.

Around the periphery of the rotary table 85 are openings 210 in which are disposed roll carrying plungers 211. The roll carrying plungers 211 are frictionally held in the table openings by means of springs 212 that are secured to the table and bear against said plungers. To prevent wear on the springs 212, bronze wear plates 213 may be interposed between the several springs and the respective plungers 211. The springs 212 are preferably secured to the table 206 by means of screws 214, said screws also providing means for varying the pressure exerted by the springs 212 on the plungers 211.

The lower end of each roll receiving plunger 211 is provided with a tapered recess 215 adapted to receive a roll 216 to be gauged. Preferably a socket piece 217 or collet of soft steel and of accurate form and shape is inserted in the socket and the roll is received in said socket piece. The size of each roll receiving socket 217 is such that the smallest roll to be gauged on the machine will be almost flush with the bottom of the opening, that is, it will project very slightly below the end of the roll receiving

member. The roll holding plungers are hollow and in the bore of each is a headed pin 218 that bears against a roll 216 and projects above the plunger and by means of which the roll may be ejected.

Referring again to the taper and roundness gauging part of the machine, said machine comprises a main drive shaft 11 vertically mounted in a framework 12 which is secured on a suitable pedestal 13. A vertically disposed rotatable positioning disk 18 is provided with pockets for receiving rolls to be gauged for taper and roundness. Said positioning disk is fixed on a hollow shaft 19 on which is a pinion 20. A pinion 24 is mounted on a stub shaft 25 that extends through said hollow shaft 19 constituting a support therefor. The pinions 20 and 24 are held in position as by nuts 26 on the end of the stub shaft and are operatively connected by suitable gearing. The shaft 25 projects beyond the positioning disk 18 and has a pinion 27 mounted on the inner end thereof, whose hub is screw threaded and has a disk 28 mounted thereon, said disk 28 being of substantially the same diameter as the positioning disk 18 hereinbefore mentioned and being spaced slightly therefrom. Said disk 28 is hereinafter called the rolling disk and is provided with driving means operating through the pinion 27, whereby the rolling disk rotates at a different speed from that of the positioning disk.

Rolls are fed to the positioning disk and as said disk rotates the rolls are prevented from dropping therefrom by a guard plate 44. The rolls are carried past a taper gauge comprising a horizontally disposed floating lever 45 whose outer end is provided with electric contact points 46 that are adapted to cooperate with fixed contact points 47 in electric circuits for operating sorting devices (such circuits and sorting devices not being shown in detail in the present application). The contact points 47 are mounted on a yoke member 49. The end of the lever 45 is forked and beveled so that when both forks 51 bear against a roll of the proper taper the other end of the lever lies midway between the fixed contact points 47. The bottom of the yoke or fork is provided with a knife edge 52 that bears against a shoe 53 which is mounted adjacent to the path of the rolls. Attached to said shoe 53 and to the lever is a spring 54 that pulls on said lever and causes its forks 51 to project into the path of rolls in the positioning disk.

After a roll has been gauged for taper, further rotation of the positioning disk 18 carries the roll past the roundness gauging device. The curved shoe 53 is mounted on a block 55 that is mounted at the end of a polygon plunger 56 which is mounted with its longitudinal axis at right angles to the plane of the positioning disk 18 so as to be

bodily movable transversely of the said disk. Preferably the plunger fits in the bore of a housing 57 provided therefor in the framework so as to be freely movable endwise therein. The plunger is provided with recesses 58 in each of which is a spring 59 that bears against a plate 60 that closes the end of the bore in which the plunger fits. Thus the plunger 56 is always forced toward the positioning disk 18 by the pressure of the springs. The back portion of the plunger 56 is hollowed out to receive a friction element that has frictional engagement with the inner wall of said bore but is capable of sliding endwise of said bore when the pressure is sufficient to overcome the frictional engagement. This friction element is in the form of a central disk 61 with cylindrical extensions 62 on both sides, the extensions being slotted inwardly from their ends to form resilient arms for yieldably engaging the inner surface of the plunger.

Attached to the central disk 61 is a rod 63 which extends through a hole provided therefor in the plate 60 and terminates in a yoke 64. This yoke has a horizontal cross pin 65 which extends through a vertically elongated slot 66 in the upper end of a link 67. Also extending through the upper portion of said slot 66 is a second pin 68 which is fixed to a stationary bracket 69 on the framework. The two pins 65 and 68 are adapted to make contact with both sides of the slot 66, the pin 68 constituting the pivot about which the link 67 swings when actuated by the pin 65. The lower end of the link 67 is placed on a yoke 72 on which extends a pin 73 on the end of an arm 74 that is mounted on a rock shaft 75. The lower portion of the slot 72 is narrow enough to hug the pin 73 on both sides thereof, but the upper portion of the slot is considerably wider than the pin, so as to permit the link 67 to swing far enough to make contact with an electrical terminal 71 when the pin is moved to the wider portion of the slot. As the positioning disk carries a roll past the roundness gauging device, the difference in the speed of rotation of the positioning disk and rolling disk causes the roll to rotate on the shoe 53. The plunger 56 is first moved in the housing 57 to accommodate itself to the size of the roll, (the lever 67 being held against movement to accommodate this adjustment). Then the shaft 75 is rocked to release the lower end of the link 67. Any variation from true circularity in the roll will cause the plunger 56 to move, thus operating the link 67 and causing one of the contact points 70 on the end of said link to contact with one of the contact points 71, thus operating an assorting or ejecting mechanism.

Rolls that have been gauged for taper and roundness are delivered from the positioning disk 18 to a horizontally disposed

rotatable distribution disk 85. Off taper and out of round rolls are ejected from the distributing disk at the gate 112 by any suitable mechanism. Such ejecting mechanism 5 need not be described in connection with the present invention.

A roll that is satisfactory as to roundness and taper is carried by the distributing disk 85 past the gate 112 to a point beneath a roll receiving plunger 211, where the toe 111 of the roll holding pawl 103 engages the cam 106 and permits the roll to rest on the top of a feed plunger 219 that is mounted on a cam disk 220 with which cooperates 10 a cam roller 221 on a cam 222 that is secured to a shaft 223 on whose end is a gear 224 that meshes with a gear, as the gear 83 on the main drive shaft 11 to be driven thereby. The cam disk 220 moves the feed plunger 20 219 upwardly forcing the roll (small end first) into the roll socket 217 of the roll receiving plunger 211 directly thereabove. As the roll sockets 217 are all of the same size, the roll will extend into the socket a distance 25 depending upon its diameter and as the stroke of the feed plunger 219 is fixed, the roll carrying plunger 211 will be moved upwardly a distance depending upon the distance that the roll projects beneath the lower 30 end of the roll receiving socket. The ejector pin 218 is raised by the roll.

The periphery of the table 206 is preferably provided with gear teeth 225 that mesh with a gear 226 that is driven in any suitable way from the main drive shaft of the machine and is timed with respect to the other parts of the machine. In the construction shown in the drawings, the gear 226 that meshes with the teeth 225 of the table is mounted on the intermediate shaft 30 that is driven from the main shaft 11 by a star wheel 31 and pin wheel 33. After the roll has been inserted in the roll receiving socket 217, the table is given a slight rotary movement, sufficient to bring the roll to a gauging 45 station.

Secured to the upper end of each roll receiving plunger 211 is a contact lever 227 that has one end formed into a contact point 228. Each contact lever 227 is provided with a spring 229 for yieldably holding it in position, and an adjusting screw 230 is provided for adjusting the position of the contact lever.

Disposed above the column 203 and secured to the bushing 204 as by screws 231 is an annular supporting plate 232 that is provided with an upstanding rib 233 around its inner periphery. Interposed between the outer peripheral portion of the annular plate and the upper surface of the rotary table is an anti-friction ring 234 whose upper surface is provided with spaced recesses for receiving felt 235 or the like to be saturated with oil.

Secured to the annular plate 232 as by the screws 231 that secure said plate 232 to the bushing 204 are blocks 236 to which are pivotally secured levers 237 whose lower ends project through openings 238 in said annular plate 232. Rotatably mounted on pins 239 projecting from said table are rollers 240 that are adapted, when the table rotates, to engage the lower ends of any of said levers 237 that are out of normal position. 70 Secured to the upper end of each supporting lever 237 is a lever 241 whose outer end 242 is adapted to contact with the ejector pin 218 of a roll holding plunger 211, to eject the roll 216 therefrom. The inner ends 243 of all of the ejector levers extend to the inner periphery of the annular plate 232 and a ring 244 is mounted on the upper end of the rib 233 of said plate to support said 75 ejector levers near their ends and act as a stop therefor. Said levers 241 are provided with shoulders 245 that engage the side of said stop ring 244, said shoulders being preferably of hardened steel. 80

Disposed above the inner rib 233 of the annular plate 232 is a tubular member 246 that is provided with slots 247 into which extend the inner ends 243 of the contact levers 241. The upper portion of said tubular member 246 has a plurality of springs 248 mounted thereon, as by pins 249, there being one spring for each ejector lever 241, and each spring 248 being connected to an ejector lever 241 as by a link 250 pivotally secured to both. The engagement of the shoulders 245 of the ejector levers 241 with the stop ring 244 prevents the ejector levers 241 from being forced downwardly by the springs 248 and links 250. An armature 251 is secured to each ejector lever 241 as by a slot 252 in the armature in which fits a pin 253 on the ejector lever. 90 100

Threaded into the bore of the tubular member 246 is a sleeve 254 that has a projecting flange 255 at the top, which flange is provided with a depending annular rib 256 that engages the springs 248 and causes them to press downwardly on the links 250 that connect said springs with the ejector levers 241. 110 115

The annular plate 232 is provided with upstanding wall portions 257 between which are mounted the cores 258 of electromagnets. The electromagnet coils 259 are mounted on said cores and are secured in position by means of a ring 260 disposed on top of them and secured to the several wall members 257 as by screws 261. The ring is provided with a fiber outer wall or cover 262. Mounted on the outer portion of each wall member 257 of the annular plate 232 is a bracket 263 that is secured to the wall member 257 as by a screw 264. The brackets 263 are insulated from each other by means of fiber washers 265 and each bracket 120 125 130

et is insulated from its securing screw 264 by a fiber sleeve 266. Each bracket 263 has a projecting lug 267 in which is mounted a contact screw 268, the several contact screws being disposed in the circular path that is followed by the contact portions 228 of the several contact levers. The ring 260 and the fiber cover 262 form an annular chamber in which is a wire 269 that is connected with an end of the wire of each of the electromagnet coils 259. The other end of said wire 269 is connected with one terminal of a source of electricity indicated at 270. The other end of the wire of each coil 259 is connected with the bracket 263 that carries its contact screw 268. The other terminal of the source of electricity 270 is grounded to the frame of the machine, and the contact levers 227 of the roll receiving plungers 211 are also grounded to the frame.

Secured to the flange 255 of the sleeve 254 as by screws 271 is a bracket member 272 that is provided with bearings 273, in which is rotatably supported a horizontally disposed shaft 274. Said shaft 274 is provided with a bevel gear 275 at the end that meshes with a bevel gear 276 on a shaft, as the main shaft 11, whereby said shaft is continuously rotated. The end of the shaft 274 is disposed above the center of the size gauging portion of the machine. Secured to the end of the shaft 274 is a cam 277 to which is pivotally secured a cam roller 278 as by a stud 279. Said cam roller 278 rides in the slot 280 of a cam 281 from which depends a plunger rod 282. The cam 277 is slidably mounted in the bracket member 272 and is held in position by means of a cap 283 that is secured to the bracket member 272 as by screws 284. Secured to the lower end of the plunger rod 282 is a mandrel 285 that moves up and down in the bore of the tubular member 246 and of the rib 233 of the annular plate 232.

At each gauging station a suitable conveyer 286 is provided to receive a roll ejected from a roll holding plunger at that station. Said conveyer deposits the rolls in a suitable receptacle 287.

Referring again to the roll holding plungers 211, it will be remembered that the contact lever 227 of a plunger will project upwardly a distance depending upon the diameter of a roll 216 therein. The several contact screws 268 are arranged in stepped relation, running from the largest to the smallest. If the roll in a roll receiving plunger 211 is of the size for which the gauge at which it stops is set, the contact screw 268 will contact with the contact point 228 of the contact lever 227, thus closing a circuit through the electromagnet and causing the armature 251 of the ejector lever 241 to be attracted. This raises up the in-

ner end 243 of the ejector lever so that the shoulder 245 is clear of the stop ring 244 on the rib 233 of the annular plate 232. The downward pressure of the spring 248 and link 250 causes this movement to be continued somewhat so that the end 243 of the ejector lever 241 projects into the bore of the tubular member 246, in position to be engaged by a shoulder 288 on the mandrel 285 as it ascends and the lever 237 to which the ejector lever 241 is secured is moved from normal position. Such arrangement raises the inner end 243 of the ejector lever 241 and lowers the outer end 242, thus causing said outer end to strike the top of the ejector pin 218 and eject the roll 216. This movement of the ejector lever 241 is accommodated by the slot and pin connection between the ejector lever 241 and the armature 251. After the roll 216 has been ejected, the next rotation of the table will bring a roller 240 into contact with each lever 237 that has been moved, thus swinging said lever 237 and its ejector lever 241 to normal position and causing the ejector lever to be reset. It will be seen from the foregoing that there are three positions of each ejector lever 241 and its associated parts: namely, first, the normal position shown in Fig. 1 in which the inner end 243 of the ejector lever 241 rests against the stop ring 244 and the armature 251 of the ejector lever is spaced away from the core 258 of the electromagnet; second, the position shown in full lines in Fig. 7, in which the armature 251 of the ejector lever 241 has been attracted by the energized core 258 of the electromagnet, the outer end 242 of the ejector lever swung downwardly slightly and the inner end 243 moved upwardly and inwardly so that it projects into the bore of the tubular member 246 in position to be engaged by the shoulder 288 of the mandrel 285, and the supporting lever 237 is moved into more or less vertical position; and, third, the position shown in dotted lines in Fig. 7 in which the inner end 243 of the ejector lever 241 has been swung upwardly by the shoulder 288 on the mandrel 285 and the outer end 242 has been swung down engaging the head of a knockout pin 218 and ejecting a roll 216 and forcing the roll holding plunger 211 down into normal position.

The operation of the machine is as follows:

A roll 216 that is satisfactory as to roundness and taper is delivered to the socket 217 of a roll holding plunger 211 by the feed plunger 219. Then the table 206 is rotated so as to bring the roll 216 to the first gauging station. Said first gauging station is set to eject all rolls that are larger than a predetermined size. The step by step rotation of the table continues until

the roll reaches the gauging station that is set for its size. At this station, the contact point 228 of the contact lever 227 of the roll holding plunger 211 makes contact with the contact screw 268 of the gauging device, thus closing the electric circuit through the electromagnet and causing the armature 251 of the ejector lever 241 to be attracted, the outer end of the ejector lever 10 depressed and the inner end raised clear of the stop ring 244. This movement is continued by the force of the spring and link and the inner end of the ejector lever is swung into the bore of the tubular member 246; and on the next upward stroke of the mandrel 285, the inner end of the ejector lever is raised and the outer end is lowered, striking the knockout pin and ejecting the roll into the conveyor 286, which delivers 20 it to a receptacle 287. The knockout movement also causes the roll receiving plunger 211 to be lowered to its lowermost position, in which it is ready to receive another roll at the feed station.

25 At the last station, there is no gauging device and the ejector lever 241 at said station is not provided with a contact shoulder, but the inner end thereof always extends into the bore of the tubular member 246. Thus, said ejector lever at the last station is operated on each upward movement of the mandrel; and any roll that is too small to be ejected at any of the preceding gauging stations will be ejected at the last station.

35 The rolls that are too large and the rolls that are too small may be gauged on other machines that are set to accommodate them.

40 After a roll has been ejected, the next rotation of the table causes a roller 240 on said table to engage the lever 237 to which is secured the ejector lever 241 that has just been operated. Said lever 237 and ejector lever 241 are thus restored to normal 45 position and the shoulder 245 on the inner end of the ejector lever engages the stop ring 244.

50 The size gauging machine shown in the drawings has sixteen gauging stations of which the first is set to eject all rolls above a predetermined size, the next fourteen are set to eject rolls of progressively smaller sizes and the last is provided with a knockout device that always ejects a roll that reaches said last station. Obviously, the machine may be made with any desired number of stations. By adjusting the contact levers and screws the machine may be arranged to gauge rolls of any desired sizes.

55 The gauging mechanism hereinbefore described has numerous advantages. When used in connection with the roundness and taper gauging machine disclosed in my said copending application, said machine auto-

60 matically gauges rolls for roundness and taper, ejects rolls that are out of round or off taper, and assorts the rolls that are correct as to roundness and taper according to their size.

65 My machine is accurate and is automatic in its operation. It may be arranged to gauge rollers of various size and tapers. Obviously numerous changes may be made without departing from the invention and I do not wish to be limited to the precise construction shown.

70 What I claims is:

75 1. A roll gauging machine comprising a taper gauging device, a roundness gauging device, a size gauging device, means for carrying rolls past the taper gauging device and the roundness gauging device to be gauged thereby, means controlled by said gauging devices for ejecting rolls that are off taper and rolls that are out of round and means for delivering to the size gauging device rolls that are satisfactory as to taper and roundness and means for coordinating the operation of said feed means with said 80 gauging devices.

85 2. A roll gauging machine comprising a taper gauging device, a roundness gauging device, means for carrying rolls into engagement with said gauging devices, a distributing disk that receives rolls that have been gauged by said taper and roundness gauging devices, means controlled by said taper and roundness gauging devices for ejecting from the distributing disk rolls that are off taper and rolls that are out of round, a plurality of size gauging devices, a roll carrier adapted and arranged to carry rolls past said size gauging devices, means for feeding from said distributing disk to said carrier rolls that are satisfactory as to taper and roundness and means for coordinating the operation of the several parts of said machine.

90 3. A roll gauging machine comprising a taper gauging device, a roundness gauging device, means for carrying rolls into engagement with said gauging devices, a rotary distributing disk that receives rolls that have been gauged by said taper and roundness gauging devices, means controlled by said taper and roundness gauging devices for ejecting from the distributing disk rolls that are off taper and rolls that are out of round, a plurality of size gauging devices arranged in stepped series, a rotary 95 roll carrier adapted and arranged to carry rolls to said size gauging devices and means for feeding from said distributing disk to said carrier rolls that are satisfactory as to taper and roundness, said roll carrier having an intermittent rotary movement, ejecting means associated with said gauging devices for ejecting rolls of the sizes for which the respective gauging devices are 100

105 110 115 120 125 130

125 130

set and means for coordinating the operation of the several parts of the machine.

4. A roll gauging machine comprising a taper gauging device, a roundness gauging device, means for carrying rolls into engagement with said gauging devices, a rotary distributing disk that receives rolls that have been gauged by said taper and roundness gauging devices, means controlled by said taper and roundness gauging devices for ejecting from the distributing disk rolls that are off taper and rolls that are out of round, a plurality of size gauging devices, a rotary roll carrier adapted and arranged to carry rolls past said size gauging devices and overlapping said distributing disk, said carrier being provided with a plurality of vertically movable roll holding plungers each having a downwardly opening tapered socket, and a feed plunger having a fixed stroke and adapted and arranged to force a roll from said distributing disk into the socket of a roll holding plunger thereabove.

25 5. A roll gauging machine comprising a roll carrying table, a plurality of roll receiving plungers movably supported in said table, each plunger having a roll receiving socket, each plunger having a contact lever thereon, a plurality of contact screws each adapted to be engaged by one of said contact levers, and means for feeding rolls to said roll carrying plungers.

35 6. A roll gauging machine comprising a roll carrying table, a plurality of roll receiving plungers movably supported in said table, each plunger having a roll receiving socket, each plunger having a contact lever yieldably mounted thereon, an adjusting screw for adjusting the position of each contact lever, a plurality of contact screws each adapted to be engaged by one of said contact levers, and means for feeding rolls to said roll carrying plungers.

45 7. A roll gauging machine comprising a roll carrying table, a plurality of hollow roll receiving plungers movably supported in said table, each plunger having a roll receiving socket, a knockout pin disposed in the bore of each plunger, each plunger having a contact lever thereon, a plurality of contact screws each adapted to be engaged by one of said contact levers, and means for feeding rolls to said roll carrying plungers.

55 8. A roll gauging machine comprising a roll carrying table, a plurality of roll receiving plungers movably supported in said table, resilient means engaging each plunger and tending to hold it in any position in which it is placed, each plunger having a roll receiving socket, each plunger having a contact lever thereon, a plurality of contact screws each adapted to be engaged by one of said contact levers, and means for feeding rolls to said roll carrying plungers.

9. A roll gauging machine comprising a roll carrying table, a plurality of roll receiving plungers movably supported in said table, resilient means engaging each plunger and tending to hold it in any position in which it is placed, each plunger having a roll receiving socket, each plunger having a contact lever thereon, a plurality of contact screws each adapted to be engaged by one of said contact levers, and means having a fixed stroke for reeding rolls to said roll carrying plungers.

10. A roll gauging machine comprising a roll carrying table, a plurality of roll receiving plungers movably supported in said table, resilient means engaging each plunger and tending to hold it in any position in which it is placed, each plunger having a roll receiving socket, each plunger having a contact lever thereon, a plurality of contact screws each adapted to be engaged by one of said contact levers, means having a fixed stroke for feeding rolls to said roll carrying plungers, and means controlled by the several contact devices for ejecting rolls of the size for which said devices are set and for restoring said plungers to normal position.

11. In a machine of the kind set forth for gauging conical rolls, a rotary table provided with downwardly opening tapered sockets, a distributing disk, a plunger adapted to engage a roll on said distributing disk and force it upwardly into a socket, a series of gauging devices and means controlled by said gauging devices for ejecting rolls of the sizes for which said gauging devices are set respectively.

12. In a machine of the kind described for gauging conical rolls, a rotary table provided with a plurality of vertically movable plungers each having a downwardly opening tapered socket, a distributing disk, a plunger adapted to engage a roll on said distributing disk and force it upwardly into a socket, a knockout pin mounted in each plunger and extending into said roll receiving socket, a series of contact devices, each plunger having a contact lever adapted to engage a contact device, and means for depressing a knockout pin to eject a roll and for depressing the plunger to normal position when the corresponding contact lever has engaged a contact device.

13. A roll gauging machine comprising a roll carrying table having an intermittent rotary movement, a plurality of gauging devices, a plurality of ejecting devices each disposed so as to be in position to eject a roll when the table is stationary at the gauging stations, means actuated by the gauging devices for tripping said ejecting devices, and a continuously reciprocating member adapted to engage any of said ejecting devices that have been tripped.

14. A roll gauging machine comprising a roll carrying table, a plurality of gauging devices, a plurality of ejecting devices each disposed so as to be in position to eject a roll when the table is stationary at the gauging stations, means actuated by said gauging devices for tripping said ejecting devices, and means for actuating any of said ejecting devices that have been tripped.
15. A roll gauging machine comprising a roll carrying table having a plurality of roll receiving plungers frictionally mounted thereon and each having a roll receiving socket therein, a knockout pin extending into each roll receiving socket, a plurality of gauging devices, a plurality of ejecting devices each disposed so as to be in position to eject a roll at a gauging station, means actuated by said gauging devices for tripping said ejecting devices, and a member adapted to engage any of said ejecting devices that have been tripped to cause them to actuate said knockout pins to eject the rolls and reset said plungers.
16. In a machine of the kind described, a supporting plate provided with an upstanding central rib portion, said rib portion being provided at the top with an annular abutment ring portion, a plurality of supporting levers pivotally secured to members provided therefor on said plate and projecting downwardly through openings in said plate, ejector levers pivotally secured to the upper ends of said supporting levers, each ejector lever having a shouldered end adapted to engage the abutment ring portion of said rib, a rotary roll carrier, a plurality of gauging devices supported on said plate, and knockout pins engaging said rolls, and means controlled by each gauging device for actuating the corresponding ejector lever.
17. In a machine of the kind described, a supporting plate provided with an upstanding central rib portion, said rib portion being provided at the top with an annular abutment ring portion, a plurality of supporting levers pivotally secured to members provided therefor on said plate and projecting downwardly through openings in said plate, ejector levers pivotally secured to the upper ends of said supporting levers, each ejector lever having a shouldered end adapted to engage the abutment ring portion of said rib, a rotary roll carrier, a plurality of gauging devices supported on said plate, and knockout pins engaging said rolls, means controlled by each gauging device for actuating the corresponding ejector lever, and means for resetting said supporting levers and ejector levers.
18. In a machine of the kind described, a supporting plate provided with an upstanding central rib portion, said rib portion being provided at the top with an annular abutment ring portion, a plurality of supporting levers pivotally secured to mounting members provided therefor on said plate and projecting downwardly through openings in said plate, ejector levers pivotally secured to the upper ends of said supporting levers, each ejector lever having a shouldered end adapted to engage the abutment ring portion of said rib, a plurality of electromagnets, one for each ejector lever, each ejector lever having an armature adapted to be attracted by an electromagnet, a rotary roll carrier, a plurality of gauging devices supported on said plate, and knockout pins engaging said rolls, said gauging devices each including means for energizing the corresponding electromagnet when engaged by a roll of the size for which the gauging device is set.
19. In a machine of the kind described, a supporting plate provided with an upstanding central rib portion, said rib portion being provided at the top with an annular abutment ring portion, a plurality of supporting levers pivotally secured to mounting members provided therefor on said plate and projecting downwardly through openings in said plate, ejector levers pivotally secured to the upper ends of said supporting levers, each ejector lever having a shouldered end adapted to engage the abutment ring portion of said rib, a plurality of electromagnets, one for each ejector lever, each ejector lever having an armature adapted to be attracted by an electromagnet, each armature having a lost-motion connection with its ejector lever, a rotary roll carrier, a plurality of gauging devices supported on said plate, and knockout pins engaging said rolls, said gauging devices each including means for energizing the corresponding electromagnet when engaged by a roll of the size for which the gauging device is set, and means separate from said electromagnets for actuating said ejector levers after their armatures have been attracted by said electromagnets.
20. In a machine of the kind described, a supporting plate provided with an upstanding central rib portion, said rib portion being provided at the top with an annular abutment ring portion, a plurality of supporting levers pivotally secured to mounting members provided therefor on said plate and projecting downwardly through openings in said plate, ejector levers pivotally secured to the upper ends of said supporting levers, each ejector lever having a shouldered end adapted to engage the abutment ring portion of said rib, a plurality of electromagnets, one for each ejector lever, each ejector lever having an armature adapted to be attracted by an electromagnet, a rotary table, roll carrying devices on said table, a plurality of gauging

- devices supported on said plate, knockout pins engaging said rolls, and cam rollers on said table adapted to engage said supporting levers to reset them and said 5 ejector levers.
21. In a machine of the kind described, an annular supporting plate provided with an upstanding rib at its inner periphery, said rib being provided with an abutment 10 ring portion at the upper end thereof, a mandrel reciprocable in the bore of said rib, a plurality of ejector levers having shouldered portions adjacent to their inner ends and abutting against said abutment 15 ring portion of said rib, a plurality of roll carrying devices arranged to travel beneath the outer ends of said ejector levers and to stop directly beneath said ejector levers, a plurality of gauging devices associated 20 with said ejector levers, means controlled by said gauging devices for swinging their associated ejector levers clear of the abutment ring and permitting the inner ends of 25 said ejector levers to extend into the bore of said rib to be engaged by said mandrel.
22. In a machine of the kind described, an annular supporting plate provided with an upstanding rib at its inner periphery, said rib being provided with an abutment 30 ring portion at the end thereof, a mandrel reciprocable in the bore of said rib, a plurality of pivotally mounted supporting levers, a plurality of ejector levers each pivotally secured to a supporting lever and 35 having a shouldered portion adjacent to its inner end and abutting against said abutment ring portion of said rib, a plurality of springs each connected with an ejector lever by a link, a plurality of roll carrying 40 devices arranged to travel beneath the outer ends of said ejector levers and to stop directly beneath said ejector levers, a plurality of gauging devices associated with said ejector levers, means controlled by said gauging 45 devices for swinging their associated ejector levers clear of the abutment ring and permitting the inner ends of said ejector levers to extend into the bore of said rib to be engaged by said mandrel.
23. In a machine of the kind described, an annular supporting plate provided with an upstanding rib at its inner periphery, said rib being provided with an abutment ring 50 portion at the end thereof, a mandrel reciprocable in the bore of said rib, a plurality of pivotally mounted supporting levers, a plurality of ejector levers each pivotally secured to a supporting lever and having a shouldered portion adjacent to its inner end 55 and abutting against said abutment ring portion of said rib, a plurality of springs each connected with an ejector lever by a link, a plurality of roll carrying devices arranged to travel beneath the outer ends of 60 said ejector levers and to stop directly be- neath said ejector levers, a plurality of gauging devices associated with said ejector levers, means controlled by said gauging devices for swinging their associated ejector levers clear of the abutment ring and permitting the inner ends of said ejector levers to extend into the bore of said rib to be engaged by said mandrel, and means for resetting said supporting levers and ejector levers.
24. In a machine of the kind described, an annular supporting plate provided with an upstanding rib at its inner periphery, said rib being provided with an abutment ring portion at the end thereof, a mandrel reciprocable in the bore of said rib, a plurality of ejector levers having shouldered portions adjacent to their inner ends and abutting against said abutment ring portion of said rib, a plurality of roll carrying devices arranged to travel beneath the outer ends of said ejector levers and to stop directly beneath said ejector levers, a plurality of gauging devices associated with said ejector levers, means controlled by said gauging devices for swinging their associated ejector levers clear of the abutment ring and permitting the inner ends of said ejector levers to extend into the bore of said rib to be engaged by said mandrel and an ejector lever whose end extends into the bore of said rib and is actuated on each stroke of said mandrel.
25. In a gauging machine of the kind set forth, a column, a rotary table having a depending bearing portion having a conical bore, a bushing interposed between said column and said bearing portion, a plurality of roll carrying members mounted around the marginal portion of said table, a plurality of gauging devices and ejecting devices associated with said gauging devices for ejecting rolls of the sizes for which the respective gauging devices are set.
26. In a gauging machine of the kind set forth, a column, a rotary table having a depending bearing portion having a conical bore, a bushing interposed between said column and said bearing portion, the periphery of said table being provided with gear teeth, a gear meshing with said teeth and means for intermittently rotating said gear, a plurality of roll carrying members mounted around the marginal portion of said table, a plurality of gauging devices and ejecting devices associated with said gauging devices for ejecting rolls of the sizes for which the respective gauging devices are set.
27. In a gauging machine of the kind set forth, a column, a rotary table having a depending bearing portion having a conical bore, a bushing interposed between said column and said bearing portion, a plurality of roll carrying members mounted around the marginal portion of said table, a plurality of gauging devices and ejecting devices associated with said gauging devices for ejecting rolls of the sizes for which the respective gauging devices are set.

the marginal portion of said table, a plate mounted on said column and overhanging said table, said plate having a plurality of upstanding projections around its margin, electromagnets between said projections, a ring secured to the tops of said projections and engaging the tops of said electromagnets, a plurality of gauging devices comprising contact devices on said roll carrying

members and contact devices on said projections and electrically connected with said electromagnets, and ejecting devices associated with said gauging devices for ejecting rolls of the sizes for which the respective gauging devices are set.

Signed at Canton, Ohio, this 19th day of January, 1925.

JEREMIAH KELLER.
